UNITED STATES PATENT OFFICE.

THOMAS C. SPELLING, OF NEW YORK, N. Y.

CLOSURE FOR BOTTLES AND OTHER CONTAINERS.

1,384,573.

Specification of Letters Patent. Patented July 12, 1921.

Application filed April 11, 1917. Serial No. 161,112.

To all whom it may concern:

Be it known that I, THOMAS C. SPELLING, a citizen of the United States, residing at New York city, have invented a new and 5 useful Improvement in Closures for Bottles and other Containers, of which the following is a specification.

This invention relates to closures for bottles and similar containers. Its purpose is 10 the provision of a receptacle for paste, glue, mucilage, ink and other substances, whether in liquid or other condition, and especially such as grease, stain, or adhere, and which it is desirable to apply or use in small measure or quantity, from time to time, and of 15 means for unsealing the bottle or container without complete detachment and removal of the closure. It is the further purpose to provide, to be used in connection with the 20 bottle or other container a convenient means for inclosing, fastening and holding a writing-pen, brush, or other implement for use with said liquid or other substance.

The invention consists in the novel construction of parts hereinafter described in 25 the specification and defined in the appended claims, and combination and coaction of the parts. In connection with the description, reference is to be had to the accompanying 30 drawings forming a part of this specification.

Figure 1 is a perspective view of a bottle of suitable form partially broken away. Fig. 2 is a sectional side view of the bottle 35 shown in Fig. 1 with the various parts in place. Fig. 3 is a plan view of the bottle with the parts in place. Fig. 4 is a plan view of the cap. Fig. 5 is a side elevation of the cap. Fig. 6 is a plan view of the grip 40 member before being bent into shape. Fig. 7 is a perspective view of the grip. Fig. 8 is a perspective view, showing the forms of the stopper, sheath and pen and the relative functions of parts in the act of extracting 45 the pen from sheath and stopper.

A few explanatory words at this point will facilitate an understanding of the detailed description. My purpose is to get rid of the inconveniences of conventional 50 stoppers for ink and mucilage bottles and similar containers, which inconveniences are well known, and avoid the necessity of the complete removal and replacement of such stoppers upon all occasions of using 55 them, or the alternative of leaving the containers unstoppable, with the result that

contents evaporate or thicken so as to be unfit for use. Unstoppable bottles or other containers are always liable to be upset, with resulting annoyance and loss. My purpose is also to obviate the inconvenience of having to provide a separate place for the pen and mucilage brush on a desk, or on occasions of the user desiring to carry them on a journey. In this device the main area 60 of the ordinary mouth is permanently sealed, and the side-mouth is opened for access to the contents, and then sealed, by simple means. A permanent receptacle through the side-mouth and inside the container is 70 also provided for the writing-pen in the case of an inkstand and the brush in the case of a container of mucilage or paste. To attain these objects, the elastic properties of india rubber, or cork, in coaction 75 with the resiliency of a metallic grip, and the imperviousness of water proof or wax paper, are utilized.

Referring more specifically to the drawings, like reference characters designating 80 like parts in the several views, the bottle is formed with the top mouth 1, the grooved formation 2 in the rim, 3, said grooved formation being hereinafter designated as a grooved vent, and has the milled edge 4 on 85 the exterior of the rim above the horizontal undercut 5. The closure for the top mouth comprises, in addition to the stopper, 20, for an opening therein, the gasket 8 underlying the cap 9, with the super-cap 10, on 90 which latter appears the words Trade mark, 11, overlying cap 9 and attached to the gasket through the perforations 12 in the cap. 12' represents a slight interior depression in the cap. The portion constituting the grip member has the leg 13 and the 95 inturned feet 14. The feet are slotted from the leg at 15, forming the inturned shoulders 16, which, being bent to an approximately horizontal plane relative to the outer 100 surface of the bottle neck, secures close contact therewith and with said horizontal undercut of the rim. The extremities of the feet are turned toward each other normally, in order that, when in place, they may grip 105 the neck of the bottle beyond its greatest diameter in right angular alinement with the leg. Obviously, in order to emplace the grip, its parts must be sprung apart, and in view of its uses it must be formed of 110 resiliant metal. To assemble the device the gasket, cap and super-cap are first united,

by the use of glue inserted through the perforations 12, or otherwise. Then the cap is pressed down over the rim and the downwardly curved legs, 17, are snapped under the rim, 3, care being taken to bring the gap in the circular row of legs into proper relation to the grooved vent 2. The grip is then emplaced, whereupon, the stopper 20 may be inserted and locked in place by pressure on the extended end, 18. Extending through the super-cap, cap and gasket, is the cutaway space 19, formed to receive and have pressed downwardly and frictionally bound therewithin the stopper 20. This stopper may be formed of cork, india rubber, or some other flexible, impervious, substance. The grip, before emplacement, has the form shown in Fig. 7. The grip is necessarily formed in irregular outline, to adapt it to its intended use. It comprises the two principal parts, the grip proper, 22, and the slotted arm, 23, the latter attached to the grip. The pivot, 26, extending through the slot, 25, carries the button, 27, to arrest and limit vertical movement of the arm, which, however, has room for horizontal movement under the button and on the pivot. The hinged arm is attached to the stopper through the thread or rivet holes, 28, and has as its free terminal the snap 29 adapted to fit under and frictionally engage the rim, 3, when the stopper is in place, to complete the act of sealing. The grip, 22, is shouldered into the depression, 12^a, as seen at 37. The hinged arm is bent centrally upward, at 38, affording a finger hold, to facilitate manipulation. Through the stopper is the aperture 30 in which a sheath 31 is placed and attached, by any suitable means, and a writing pen or mucilage brush, or other adaptable implement, may be inserted therein, and withdrawn therefrom as occasion may require. The sheath 31, formed for use in connection with a pen is closed at its lower end to protect the point of the pen from contact with liquids. The upper portion near the end, of the penstock will be reduced and given an elliptical shape, in order to fit it to the sides of the opening through the stopper. To utilize the invention, a finger may be placed under the end, 18, and the stopper extracted with upward pressure. The pressure of the material of the stopper around the top end of the writing pen or brush being now relaxed, it may be pulled out. The stopper may be then moved out of the opening which it is used to seal by a combination of upward and backward pressure. The replacement of the sealing parts is accomplished by action too simple to require description. The uses of the grooved vent 2 are more apparent where the contents of the bottle or other container are such that they flow freely than where they consist of

mucilage, glue, paste or like substance; nevertheless the presence of the grooved vent will be found to facilitate the use of the brush or other implement in the use of these substances.

By the foregoing description it is not my intention to limit the construction of the invention thereto, but I realize, as will all familiar with the art to which it appertains, that a variety of other forms are within its principle.

Having fully described the invention, I claim:

1. A closure for a bottle formed with a vent in the rim surrounding the mouth, the rim being horizontally undercut, comprising a cap formed of resilient substance, attached to, and fitted on, and creased along its outer edge inside of the rim, overlying a gasket of yieldable substance, both co-extensively covering less than the entire area within the rim, a stopper, and means for shifting the stopper into and out of said space, and binding and locking it when in place.

2. A closure for a bottle formed with a vent in the rim surrounding the mouth, the rim being horizontally undercut, comprising a cap formed of resilient substance, attached to, and fitted on, and creased along its outer edge inside of the rim, overlying a gasket of yieldable substance, both co-extensively covering less than the entire area within the rim, a stopper, and means for shifting the stopper into and out of said space, and binding and locking it when in place, the means consisting of an arm attached to the stopper, slotted centrally, having horizontal movement throughout the length of the slotted section on and about a pivot formed on a grip member supported on the cap, the arm also having detachable, resilient and frictional engagement on and under the rim and shoulder of the bottle.

3. The combination of a closure for a bottle member formed with a vent in the rim surrounding the mouth and a shoulder on the neck below the rim, the interior of the rim milled, the closure comprising a cap formed of resilient substance, attached to, and fitted on, and creased along its outer edge inside of the rim, overlying a gasket of yieldable substance, both co-extensively covering less than the entire area within the rim, a stopper of any suitable substance formed and shaped to occupy and close the remaining space inside the rim, including the vent space, with means for shifting the stopper into and out of said space, and binding and locking it in place, the means consisting of an arm attached to the stopper, slotted centrally, having horizontal movement throughout the length of the slotted section on and about a pivot formed on a grip member supported on the cap, the

arm also having detachable resilient and frictional engagement on and under the rim of the bottle.

4. In a combination of a closure and means for binding and locking a stopper in place and for shifting it into and out of place, a stopper member of yieldable substance and irregular contour, formed with an opening centrally therethrough, the opening 10 rounded with a wall shaped and dimensioned to grip a penstock or other small article of a size and form corresponding approximately with the form and dimension of the opening.

15 5. A closure for a bottle, comprising a cap member of metal overlying and adhering to a gasket of pliable yieldable substance impervious to liquids, the cap, so formed, seated on the rim around the mouth of the

20 bottle and there held by continuous resilient force applied to it, the cap covering less than the entire circumference of the rim and less than the entire area within the rim, a stopper of yieldable substance occupying the

25 remaining area within the rim, including the vent space, resiliently and frictionally confined between the uncovered portion of the rim and adjacent portions of the cap, and means for securing the cap on the rim of

30 the bottle, the means consisting of a grip member, the grip member formed with inwardly turned downwardly projected legs, resiliently supported on the bottle by means of laterally extended feet, the upper margins

35 of the feet separated to the extent of part of their width from the leg portion and bent into a position of alinement with the outer surface of the bottle, the grip member having binding engagement on the cap

40 through a downwardly extended shoulder seated in a crease in the cap.

6. A closure for a bottle comprising a cap member of resilient material overlying and adhering to a gasket of pliable yieldable sub- 45 stance impervious to liquids, the cap seated on the rim around the mouth of the bottle

and there held by continuous resilient force applied to it, the cap covering less than the entire circumference of the rim and less than 50 the entire area within the rim, and a stopper of yieldable substance occupying the remaining area within the rim, including space left in the rim for a vent, the stopper resili-

55 ently and frictionally confined between the covered portion of the rim and adjacent portions of the cap by an arm member attached to the stopper, the arm slotted centrally around and about pivot means formed on a gripping member supported on the cap, both

60 arm and stopper having movement horizontally throughout the length of the slotted section under a button, the button being secured to the upper terminal of the pivot means.

65 7. A closure for a bottle comprising a cap

member of metal or other resilient material overlying and adhering to a gasket of rubber or other pliable yieldable substance impervious to liquids, the cap, so formed, seated on the rim around the mouth of the bottle and there held by continuous resilient force applied to it, the cap covering less than the entire circumference of the rim and less than the entire area within the rim, a stopper of rubber, cork, or other yieldable substance occupying the remaining area within the rim, including space left in the rim for a vent, and an arm member for resiliently and frictionally confining the stopper between the uncovered portion of the rim and adjacent portions of the cap, the free end of the arm beyond the portion attached to the stopper curved downwardly and again inwardly toward the outer surface of the bottle under the rim thereon, constituting a lock for the arm in place.

8. A closure for a bottle comprising a cap member of metal or other resilient material overlying and adhering to a gasket of rubber or other pliable yieldable substance impervious to liquids, the cap, so formed, seated on the rim around the mouth of the bottle and there held by continuous resilient force applied to it, the cap covering less than the entire circumference of the rim and less than the entire area within the rim, a stopper of rubber, cork, or other yieldable substance occupying the remaining area within the rim, including space left for a vent in the rim, and an arm member for resiliently and frictionally confining the stopper between the uncovered portion of the rim and adjacent portions of the cap, the free end of the arm beyond the portion attached to the stopper curved downwardly and again inwardly toward the outer surface of the bottle under the rim thereon, constituting a lock for the arm in place, the arm having a finger hold formed therein consisting of a portion of the arm bent and curved upwardly on the stopper.

9. The combination of a bottle member, a closure therefor, means for shifting the closure in and out of the mouth of the bottle, the bottle formed with a vent in one side of the mouth, the upper surface of the rim around the mouth milled for more effective frictional engagement with the closure.

10. In the article described a bottle member, the bottle formed with a horizontally undercut rim adapted to engage closure-fastening means, with a vent in the rim for the egress of flowing substances, the upper surface of the rim milled to secure intimate engagement of a gasket with the rim, for sealing purposes.

11. A closure for a container comprising a cap member of resilient material, overlying a gasket of pliable material, the cap and gasket seated on a milled rim around the

mouth of a container and covering less than the entire circumference of the rim and less than the entire area within the rim, and a stopper of suitable material, occupying the 5 remaining area within the rim.

12. In a combination of a bottle with a closure therefor, the closure attached to means for shifting a stopper for an opening between the cap and rim into and out of 10 place, the sub-combination of the bottle member formed with a cap overlying a gasket and a stopper, together constituting a seal, substantially as set forth.

13. In a combination of a bottle and

closure, a bottle member formed with a vent 15 for the egress of liquids and other flowing substances, the rim horizontally undercut, its upper surface milled to coact with a gasket to make a seal.

In testimony whereof, THOMAS C. SPELLING, 20 has signed his name to this specification in the presence of two subscribing witnesses, this 28th day of March, 1917.

THOMAS C. SPELLING.
